UNITED STATES PATENT OFFICE.

FRANCIS M. CASE, OF CLEVELAND, OHIO, ASSIGNOR TO EDWARD C. MCKAY, OF CLEVELAND, OHIO.

LOADER FOR MACHINE-GUN MAGAZINES.

Application filed May 13, 1918. Serial No. 234,092.

To all whom it may concern:

Be it known that I, FRANCIS M. CASE, citizen of the United States, residing at Cleveland, in the county of Cuyahoga and State of Ohio, have invented certain new and useful Improvements in Loaders for Machine-Gun Magazines, of which the following is a specification.

This invention relates to loaders for machine gun magazines, and more particularly to loaders for the disc magazine of a Lewis or similar machine gun. The object of the invention is to provide an improved loader which will take the cartridges individually from clips, or from cartons, which will load them into the magazine without missing or jamming, which is so constructed as to enable the magazine to be readily attached to or detached from the loader, which will 10 also serve as an unloader when desired, and which operates at a very greatly increased speed over prior loaders for the same purpose.

Further objects of the invention are in part obvious and in part will appear more in detail hereinafter.

The invention comprises the construction and arrangement of parts hereinafter described and claimed.

In the drawings, which represent one embodiment of the invention, Fig. 1 is a plan view; Fig. 2 is a side elevation, one of the supply chutes being omitted; Fig. 3 is a detail section on the line 3—3, Fig. 4; Fig. 4 is a sectional plan view on the line 4—4, Fig. 8, parts being broken out to expose underlying parts; Fig. 5 is a detail sectional view on the line 5—5, Fig. 8; Fig. 6 is a sectional plan view on the line 6—6, Fig. 5; Fig. 7 is a sectional elevation on the line 7—7, Fig. 1; Fig. 8 is a sectional elevation on the line 8—8, Fig. 1; Fig. 9 is a detail front elevation, partly in section, of one of the supply chutes; Fig. 10 is a sectional elevation thereof on approximately the line 10—10, Fig. 1; Fig. 11 is plan view of another form of supply chute; Fig. 12 is a side elevation of the upper portion thereof; and Fig. 13 is a front view thereof.

For clearness of description of the present invention considerable reference must be made to the magazine to be loaded, because it is so intimately related to the loader when in co-operative relation thereto. The drawings illustrate the magazine of a Lewis gun,

although it will, of course, be understood that said magazine may be used with other suitable machine guns and that the loader here to be described can be utilized for loading other types of magazines, the one shown in the drawings being referred to purely for purposes of illustration.

The magazine illustrated is of the disc type. It comprises a central hub 1 provided with an axial opening 2, said hub being provided with a rib 3 forming a channel 4 having two annular portions connected by a spirally extending portion. The lower portion of said hub has secured thereto a disc 5 whose peripheral portion supports in swivelled relation to said hub the pan 6, the periphery of which is corrugated to provide external recesses 7 and internal recesses 8, each inwardly extending corrugation being provided with a plate 9 whose side edges overlap the inner recesses 8 and are adapted to enter the annular groove 10 at the butt end of the cartridge 11, so as to confine the cartridges in the inner recesses or seats 8 when they are introduced thereto. The disc or bottom portion of the pan 6 has secured to its center an annular ring member 12 carrying a series of upright pins 13, which surround and lie closely adjacent to the hub 1, and which in number are equal to the number of recesses or seats 8 and are spaced around the central axis intermediate said seats. When the cartridges are in the magazine the pins engage reduced shoulders 14 on the cartridges and space them from each other.

The central hub 1 is a rotatable relative to the pan and pins, but normally, or when the pan is detached from the loader or the machine gun, said hub is held non-rotatable. For this purpose the member 5 carries a latch 15, Fig. 5, which extends upwardly into the aperture 2 and has a hooked locking portion 16 and whose base is pressed laterally by a compression spring 17 to engage its opposite end 18 with one of a series of recesses 19 in a part 20 which may be a portion of the pan or the ring 12. By reaching beneath the pan and pressing back the latch 15 the hub may be released so as to rotate freely relative to the pan or vice versa.

The loader now to be described is arranged to receive the magazine and to hold the same in co-operative relation with the loader and with the magazine hub rotatable relative to the pan. As the cartridges are introduced

with their butt ends in the recesses 8 the hub and pan are relatively rotated to cause the cartridges to travel along the spiral groove 4 and simultaneously downward along the 5 seats 8 so as to thread them into the magazine. The loader may be so constructed that either the pan or the hub is the stationary part, the other part being turned relatively thereto. In other words, if desired, the 10 loader may be so constructed that the pan may be held stationary and the hub rotated, in which case the supply chutes of the loader will travel around the pan with the hub. The drawings, however, illustrate the 15 reverse arrangement, in which the hub is held stationary and the pan is rotated relatively thereto.

The support for the hub is a tubular member 21 having an external key 22 and an enlarged lower portion provided with a chamber 23 in which is an annular shoulder 24. The hub 1 has a key-way 25 to receive the key 22. The hub may be slid up upon the number 21 with the key in the key-way, 25 thereby pressing back the latch 15, and when finally pushed home the latch 15 is released sufficiently to engage over the shoulder 24, as shown in Fig. 5, thereby retaining the magazine upon the member 21. In this position of the latch the dog or tooth 18 thereon is released from the teeth 19 so that the pan is rotatable relative to the hub. In removing the pan from the hub the latch 15 is pressed back and the pan pushed downwardly. To assist in pushing it off from member 21 the latter may be provided with a central opening extending clear to its top in which may be inserted a rod or plunger 26, whose lower end can be used to press 40 down on the latch 15.

Supporting post 21 may be provided with any suitable means for holding it firmly while operating the loader. For example, it may be provided with a surrounding sleeve 45 27 clamped against a shoulder 28 by the nut 29. Said sleeve may be provided with a suitable handle, such as indicated at 30, Fig. 8. By supporting the loader with this handle the pan may be turned relatively to 50 the hub or vice versa. The drawings also show the sleeve 27 provided with a lateral arm or extension 31 whose outer end portion may be secured to a table or other suitable support 32, such as by the bolts 31". This 55 arrangement makes the hub the stationary member and the pan is rotated relatively thereto.

Between the lower end of sleeve 27 and a second shoulder on the post 21 is a plate 60 member 33, the nut 29 thereby holding said plate non-rotatable relative to the hub. At one point the outer portion of the plate 33 is cut away on one side of the central axis to form a tongue or guide 34 which is bent 65 downwardly into spiral form. This tongue

is so located relative to the key 22 as to lie directly opposite the spiral portion of the rib 3 of the pan hub when the magazine is attached to the loader, and its spirality is the same as that of said rib. Plate 33 also carries, either integral or attached thereto, a second tongue 35 which lies above said plate and has a similar spirality to the tongue 34. This tongue 35 lies directly above the recess or gate 36 in the hub 1 and through which 70 the cartridges are threaded into the magazine. It therefore forms a guide for assisting in introducing the cartridges into the magazine.

Plate 33 forms a support for a rotatable 80 feeding member or transfer device. The main function of said device is to feed the cartridges into the magazine one by one, but when a supply chute is used in connection with the loader as hereafter described, it also 85 serves to transfer the cartridges from the chute or chutes to the magazine. This feeding device includes an outer ring member 37 whose inner diameter is substantially the same as the diameter of the pan across the 90 cartridge receiving recesses 8, and whose outer diameter is somewhat greater than the pan. Said member is provided with a series of inwardly extending radially disposed arms or walls 38 whose inner ends lie directly over the pins 13. Said arms are tapered and each two adjacent arms form therebetween a cavity pocket or compartment 39 of proper size to hold a single cartridge, with sufficient clearance for the cartridge to freely turn or roll in the compartment. The order and arrangement of the compartments in the feeding device is the same as those in the magazine except, of course, that the magazine may be in plural 100 form and arranged to hold one, two, three or more layers of cartridges, and because the compartments of the feeding device always lie in the same relationship to those of the magazine the feeding device may be said to 110 be in phase with the magazine. Member 37 is confined upon the plate 33 in a manner to rotate thereon by means of a series, five being shown, of small clips or plates 40 which are secured to the bottom of member 37 by 115 screws 41 and which extend inwardly beneath plate 33 as shown in Fig. 3. The spiral tongue portion 34 of plate 33 is provided with a notch or recess 42 to enable said clips to pass through the same when rotating 120 the feeding member. Said member, at one point in its periphery is also provided with a downwardly extending projection or ear 43. When assembling the pan upon the loader the key 22 must not only be introduced into the key-way 25 but the arms 38 of the feeding member must be turned until they are directly opposite or radially disposed with reference to the pins 13, and in this latter position the tongue 43 enters one 130

of the external recesses 7 in the pan, so that the pan is properly orientated with reference to the compartments of the feeding member.

As illustrated in Figs. 3 and 8 the dividing arms 38 of the feeding member travel around upon the upper surface of the plate 33 as the pan is rotated around the hub. Consequently, by introducing a cartridge into each of the compartments 39 rotation of the feeding member in the clock-wise direction, Fig. 1, causes said cartridges to roll around upon the plate 33 until they meet the tongues 34 and 35, which direct them into the spiral channel 4 of the hub. Since each arm 38 lies opposite a pin 13 the compartments of the feeding member are in alignment with the seats 8 of the pan. Therefore, as the cartridges are threaded into the channel 4 their inner ends move downwardly between the pins 13 and their outer ends in the seats 8. It should also be noted that the large body portions of the cartridges are slightly conical or tapered, so that they roll on a flat surface in a circle. This circle of roll is of larger diameter than the feeding member 37. Therefore, as the feeding member rolls the cartridges around upon the plate 33 they have a tendency to move radially outward, so that their butt ends constantly 30 press out outwardly on the feeding member. This tendency assists in introducing their butt ends into the seats 8.

While the cartridges may be inserted individually into the compartments of the feeding member the loader is preferably also provided with chute devices delivering into the feeding member and capable of receiving cartridges in quantity. Two different forms of chute are preferably provided, one into 40 which the cartridges are fed from cartons and the other for receiving them from clips, although other forms of chute may also be used if desired.

The supply chutes are usually located substantially diametrically opposite the gate or opening through which the cartridges are threaded into the pan. Any suitable number of chutes may be used, and if a plurality are used all of them may be of the carton form 50 or of the clip form or one or more of each form may be employed. The drawings show the loader equipped with one chute for clip cartridges and two others for carton cartridges.

All of the supply chutes are supported by the lateral arm or extension 31 of the central sleeve 27, whose intermediate portion is sector shaped in plan view, and is provided with a series, three being shown, of 60 radially extending slots or openings 44. The upper surface of the sector shaped portion of arm 31 is provided along each edge of the openings 44 with recesses or channels 45 to receive ribs 46 on the bases 47 of the supply chutes, which are secured to arm 31 by

screws 48. The several chutes fit interchangeably in any of the three positions on the arm, so that they can be located as desired and can be of either type shown.

The clip cartridge receiving supply chute 70 comprises two side walls 49, preferably slotted to save weight and for inspection purposes and connected by a rear wall 50 provided with a vertical slot 51 in its upper portion. Said side walls on their inner faces 75 are also provided with channels 52 which form guides for an unclipping member 53, having side walls 54 and a fairly thin rear wall 55 to which is attached a finger piece 56 extending through the slot 51, and by 80 means of which member 53 may be elevated. At the upper end of the device is a co-operating thumb piece 57. The side walls of the chute at their upper ends are provided with lugs 58 on which are pivotally mounted 85 dogs 59 whose outer portions 60 serve as counter-weights to normally hold them in positions shown in full lines, Fig. 9, in which positions their inner latch ends 61 are substantially horizontal and extend inwardly over the channel of the chute.

Fig. 10 illustrates several cartridges in a clip of common form, said clip including the channeled body portion 62, in which is the yielding or springback 63 whose opposite 95 ends are provided with teats 64 which are bent up to hold the cartridges in the clip. When cartridges are supplied in this form the filled clip is pushed down into the chute until the side portions of the clip rest upon 100 the side walls of the unclipping device, as indicated at 65. The latches 61 readily yield as the cartridges move downward, as indicated by the dotted lines in Fig. 9. In the normal position of the unclipping device the 105 finger hold 56 rests on the bottom of the slot 51, allowing all of the cartridges to be introduced into the chute to a position below the locking dogs. By then applying the 110 thumb to the thumb hold 57 and the fingers to the finger hold 56 the unclipping device can be raised. The upper cartridge is held back in the chute by the locking dogs, as shown in Fig. 10, so that continued upward movement of the unclipping device 115 bends back the lower teat 64, slides the clip off from the cartridges and ejects the clip from the chute. Usually the teat 64 yields or bends suddenly so that the clip is ejected with a quick snapping movement and all 120 five of the cartridges drop together to the bottom of the chute, although in Fig. 10 only three cartridges are illustrated for the sake of clearness.

The chute can, of course, be made of any 125 desired size, preferably being of a size to receive the contents of two or more clips.

Some cartridges are packed in cartons holding twenty cartridges in two rows of ten each, said cartons being provided with a re-

- movable cover which exposes the butt ends of the cartridges. Such cartridges are filled into the form of chute now to be described. This chute includes a base 47, such as before described, together with an upright chute portion 66 provided with a channeled seat 67 to receive the butt end of the cartridge and two oppositely disposed ribs 68 to enter the annular groove 10 of said cartridge.
- 10 On the chute is mounted for vertical sliding movement a weight 69 shown as a heavy metal member channeled out to receive and partially surround the chute. This weight carries a pivotal dog 70 which lies at the back 15 of the chute and whose inner end 71 normally extends through a vertical slot in the back of the chute, the outer portion of said dog being provided with a heavier portion 73 serving as a counter-weight. The carton 20 cartridges are filled into this chute without removing them from the carton by merely introducing the butt ends of the cartridges into the upper end of the chute. To assist in this operation the upper end of the chute 25 may be provided with an inclined guide 74. When the cartridges are in the chute the carton is pulled away. The weight 69 is then raised, its pivoted dog 71 yielding as it passes the cartridges, and when it is above 30 the cartridges said dog swings inwardly into position above the upper one thereof. This weight then produces a constant downward pressure which advances the cartridges downwardly along the chute and prevents 35 them from sticking therein.

In use of the loader with filling chutes of either or both of the types described the chutes are loaded with cartridges. The cartridges therein rest upon the feeding member, and as the latter is rotated therebeneath the lowermost cartridge in the chute enters the first vacant compartment that comes beneath the chute. The cartridges therein is then rolled around and into the magazine 45 pan. By keeping the chutes full and rotating the feeding device the cartridges are rapidly transferred to the magazine, and without the operation of any reciprocating or intermittently moving part, as a result of 50 which the loading operation is very rapid.

The device may also be used as an unloader for magazines. As illustrated the radially dividing walls 38 of the feeding members terminate at their inner ends some distance from the central sleeve 27. At one point the plate 33 supports an unloading member 75 formed of upper and lower plates 76, 77 connected by a radially extending vertical wall 78 and having inner tongue portions 79, 80 extending around the central sleeve and bent to spiral form. The spiral tongue 80 on the lower plate extends down to substantially the level of plate 33.

If a loaded magazine is attached to the un- 65 loader and the feeding device 37 is rotated

in the backward or unloading direction, that is, in a counter clock-wise direction, Fig. 1, the cartridges are unwound from or threaded out of the magazine and rolled around upon plate 33. When their inner ends reach the 70 spiral tongue 80 they ride up upon the same and are discharged radially outward over the horizontal portion 81 of the lower plate 77. The unloading operation can be performed just as rapidly as the loading opera- 75 tion, the cartridges being pushed out over the edge of the loader and dropping into any suitable receptacle.

Preferably the upper and lower plates of the unloader and also the plate 33 are pro- 80 vided with aligned openings 82. These openings enable the operator to look down through the device and see the key 22 and align with said key the key-way 25 when applying a magazine to the unloader.

The apparatus described is of relatively simple construction, is so constructed as to avoid jamming, and enables cartridges to be loaded into or withdrawn from the magazines with certainty and at a very greatly in- 90 creased speed.

What I claim is:

1. A loader for magazines having lengthwise radially extending cartridge receiving pockets, comprising cartridge carrying means adapted for connection to the magazine and having lengthwise radially extending cartridge receiving pockets whose order and arrangement are like those of the magazine.

2. A loader for magazines having length- 100 wise radially extending cartridge receiving pockets, comprising cartridge carrying means adapted for connection to the magazine and having lengthwise radially extend- 105 ing cartridge pockets whose order and arrangement are like those of the magazine, and means co-operating therewith for transferring the cartridges to the magazine.

3. A loader for magazines having length- 110 wise radially extending cartridge receiving pockets, comprising cartridge carrying means adapted for connection to the magazine and having lengthwise radially extend- 115 ing cartridge pockets whose order and arrangement are like those of the magazine, and means normally withholding the cartridges from the magazine.

4. A loader for magazines having length- 120 wise radially extending cartridge receiving pockets, comprising cartridge carrying means adapted for connection to the magazine and having radially extending cartridge receiving pockets whose order and ar- 125 rangement are like those of the magazine, means normally withholding the cartridges from the magazine, and means whereby relative movement between said cartridge carrying means and a part of the magazine feeds the cartridges into the magazine.

5. A loader, for magazines having lengthwise radially extending cartridge receiving pockets, comprising cartridge carrying means adapted for connection to the magazine and having radially extending cartridge receiving pockets whose order and arrangement are like those of the magazine, means normally withholding the cartridges from the magazine, and means whereby relative movement between said cartridge carrying means and a part of the magazine feeds the cartridges in consecutive order into the magazine.
6. A loader for pan magazines having relatively rotatable hub and pan members and lengthwise radially extending cartridge receiving pockets, comprising cartridge carrying means adapted for operative connection to said magazine and thereby rotatable around the axis of said hub member, said means being provided with lengthwise radially extending cartridge holding compartments.
7. A loader for pan magazines having relatively rotatable hub and pan members, comprising cartridge carrying means adapted for operative connection to said magazine and thereby rotatable relatively to its hub member, said means being provided with lengthwise radially extending cartridge holding compartments whose order and arrangement are like those of the magazine.
8. A loader for pan magazines having relatively rotatable hub and pan members, comprising cartridge carrying means adapted for operative connection to said magazine and thereby rotatable relatively to its hub member, said means being provided with lengthwise radially extending cartridge holding compartments whose order and arrangement are like those of the magazine, and co-operating means for transferring the cartridges to the magazine.
9. A loader for pan magazines having relatively rotatable hub and pan members, comprising cartridge carrying means adapted for operative connection to said magazine and thereby rotatable relatively to its hub member, said means being provided with lengthwise radially extending cartridge holding compartments whose order and arrangement are like those of the magazine, and means whereby relative rotation of the pan and hub members transfers the cartridges to the magazine.
10. A loader for pan magazines having relatively rotatable hub and pan members, comprising cartridge carrying means adapted for operative connection to said magazine and thereby rotatable relatively to its hub member, said means being provided with lengthwise radially extending cartridge holding compartments whose order and arrangement are like those of the magazine, and means whereby relative rotation of
- said hub member and cartridge carrying means transfers the cartridges to the magazine.
11. A magazine loader, comprising a member adapted for connection to the magazine and having at least three lengthwise radially extending compartments for holding cartridges with their longitudinal axes in the same plane and in like order and arrangement with the compartments of the magazine.
12. A magazine loader, comprising a member adapted for connection to the magazine and having at least three lengthwise radially extending compartments for holding cartridges with their longitudinal axes in the same plane and in like order and arrangement with the compartments of the magazine, and means for transferring the cartridges from said member to the magazine.
13. A magazine loader, comprising a member adapted for connection to the magazine and having at least three lengthwise radially extending compartments for holding cartridges with their longitudinal axes in the same plane and in like order and arrangement with the compartments of the magazine, and means for transferring the cartridges in consecutive order from said member to the magazine.
14. A loader for pan magazines having relatively rotatable hub and pan members and lengthwise radially extending cartridge receiving compartments, comprising a cartridge holding member rotatable in phase with the pan and having a like order and arrangement of cartridge holding compartments.
15. A loader for pan magazines having relatively rotatable hub and pan members, comprising a cartridge holding member rotatable in phase with the pan and having a like order and arrangement of cartridge holding compartments, and means whereby rotation of said member threads the cartridges into the hub.
16. A loader for pan magazines having relatively rotatable hub and pan members, comprising a cartridge holding member rotatable in phase with the pan and having a like order and arrangement of cartridge holding compartments, and means whereby rotation of said member threads the cartridges in consecutive order into the hub.
17. A loader for pan magazines having relatively rotatable hub and pan members and having lengthwise radially extending cartridge receiving compartments, comprising a support adapted for fixed connection to the hub and carrying a plate covering all the pan compartments, said plate having a gate therein, and means for threading cartridges through said gate into the pan member.

18. A loader for pan magazines having relatively rotatable hub and pan members and having lengthwise radially extending cartridge receiving compartments, comprising a support adapted for fixed connection to the hub and carrying a plate covering all the pan compartments, said plate having a gate therein, and means for threading cartridges through said gate into the pan member by relative rotation of said pan and hub members.

19. A loader for pan magazines having relatively rotatable hub and pan members, comprising a support adapted for fixed connection to the hub and carrying a plate covering all the pan compartments, said plate having a gate therein, and a cartridge feeding member movable above said plate.

20. A loader for pan magazines having

relatively rotatable hub and pan members, comprising a support adapted for fixed connection to the hub and carrying a plate covering the pan compartments, said plate having a gate therein, and a cartridge feeding member movable above said plate and having compartments whose order and arrangement are like those of the pan member.

21. A loader for pan magazines having relatively rotatable hub and pan members, comprising a support adapted for fixed connection to the hub and carrying a plate covering all the pan compartments, said plate having a gate therein, a cartridge feeding member movable above said plate, and means for supplying cartridges to said feeding member.

In testimony whereof I affix my signature.

FRANCIS M. CASE.
